DEVICE FOR CHANGING THE STROKE
OF SLURS

Paul Tuchscherer, Chemnitz, Germany, assignor
to Schubert & Salzer Maschinenfabrik Aktien-
gesellschaft, Chemnitz, Germany

Application July 31, 1940, Serial No. 348,986
In Germany August 1, 1939

6 Claims. (Cl. 66—110)

The present invention relates to a device for changing the stroke of slurs provided in flat knitting machines.

Various devices for changing the stroke of slurs are known most of which are so constructed as to allow a plurality of changing possibilities of the stroke of the slurs. Some of these devices may continuously be adapted to the width of the fabric. This renders superfluous an arrangement of a complicated system of levers and rods as well as a reversing link provided with a displaceable link block.

In a known device allowing a single change of the stroke of the slurs two swingable arms having different swinging amplitudes or different length respectively are used. The swingable arm having the larger length is used up to the width of the fabric after narrowing of the calf has been effected, whereupon the swing arm having the shorter length is used until the toe point is finished.

The use of two swingable arms is complicated and expensive and requires slides separated from each other for driving the slurs connecting bar.

In accordance with the present invention the device for changing the stroke of the slurs is substantially simplified and cheaper and, moreover, a much more successful operation of the device is obtained.

To this end a swingable arm adapted to be adjusted to two different operative lever lengths and a driving slide for the slurs connecting bar provided with two corresponding connecting points are provided to obtain a single change of the stroke of the slurs.

In the accompanying drawing one construction of the device according to the invention is shown by way of example.

In this drawing:

Fig. 1 is a front elevation of the device showing the swingable arm adjusted to the longer operative lever length.

Fig. 2 illustrates the side view of the device shown in Fig. 1.

Fig. 3 is a front elevation of a portion of the device for adjusting the swingable arm.

Fig. 4 shows a side elevation of the device illustrated in Fig. 3.

Fig. 5 is a front elevation of a portion of the device showing the swingable arm adjusted to the shorter operative lever length, and

Fig. 6 is a side elevation of the device shown in Fig. 5.

The swingable arm 1 is rotatably mounted upon a shaft 2 and is driven in a well known

manner by way of a rod 3 from the draw cam 4 of the knitting machine. Fixed to the swingable arm 1 is a small block 5 in which a double-armed lever comprising arms 6 and 7 is swingably mounted. Linked to the lever arms 6 and 7 are bolts 8 and 9 respectively which are guided in bores 10 and 11 respectively provided in the swingable arm 1. The lever arm 6 has an extension formed as a handle 12.

Displaceably mounted upon rods 13 and 14 is a driving slide 15 which is connected to the slurs connecting bar 16. In the slide 15 a member 17 is vertically displaceably mounted which is provided with connecting points 18 and 19 in form of bores registering with the bores 10 and 11 of the swingable arm 1 respectively as may be seen from Figs. 2, 4 and 6.

The operation of the device according to the invention is as follows:

To obtain a larger stroke of the slurs, the swinging movement of the swingable arm 1 is transferred to the driving slide 15 in the position of the individual elements shown in Figs. 1 and 2. By adjusting the handle 12 in the direction of the arrow X shown in Fig. 4 the bolt 8 carried by the lever arm 6 engages the connecting point or bore 18 of the member 17 (Fig. 2).

To obtain a smaller stroke of the slurs, the handle 12 is adjusted in the direction of the arrow y shown in Fig. 4, whereby the bolt 9 carried by the lever arm 7 engages the connecting point or bore 19 of the element 17 (Fig. 6).

If the double-armed lever is shifted while the swingable arm 1 occupies the vertical position disconnection of the bolt 8 and simultaneously connection of the bolt 9 to the driving slide 15 is positively effected.

The swingable arm 1, therefore, may be adjusted to two lever lengths of which the large one is effected by way of the bolt 8 and the shorter one by way of the bolt 9. The connection of the driving slide 15 to the swingable arm 1 adjusted to the larger length of the lever, therefore, results in a larger stroke of the slurs than the connection of the swingable arm 1 adjusted to the smaller lever length.

Instead of controlling the bolts 8 and 9 commonly and positively, they may also be engageably and disengageably arranged separated and independent from each other.

It is, moreover, of no importance for the essential feature of the invention whether the common positive control of the bolts is effected by hand or automatically.

What I claim is:

1. A device for changing the stroke of slurs in flat knitting machines, comprising a swingable arm adapted to be adjusted to two different operative lever lengths and a driving slide for the slurs connecting bar provided with two connecting points for a single change of the stroke of the slurs.
2. A device as set forth in claim 1 in which a double-armed lever swingably mounted on said swingable arm is used for adjusting said swingable arm two different lever lengths, said double-armed lever being linked to bolts which are guided in bores of said swingable arm.
3. A device as set forth in claim 1 in which the driving slide for said slurs connecting bar carries a vertically displaceable member which is provided with connecting points corresponding to the bores in the swingable arm to connect

said bolt of said swingable arm to said vertically displaceable member.

4. A device as set forth in claim 1 in which the adjustment of the swingable arm to two different operative lever lengths is positively effected by way of commonly controlled bolts of a double-armed lever.

5. A device as set forth in claim 1 in which the adjustment of the swingable arm to two different operative lever lengths is independently effected by way of separately controlled bolts.

6. A device as set forth in claim 1 in which the adjustment of the swingable arm to two different operative lever lengths is positively effected by way of commonly controlled bolts of a double-armed lever, said adjustment being effected by hand.

PAUL TUCHSCHERER.
